UNITED STATES PATENT OFFICE.

WILSON BROWN, OF YORK, PENNSYLVANIA.

RAILROAD-RAIL-JOINT CHAIR.

SPECIFICATION forming part of Letters Patent No. 340,415, dated April 20, 1886.

Application filed September 24, 1885. Serial No. 177,977. (No model.)

To all whom it may concern:

Be it known that I, WILSON BROWN, a citizen of the United States, residing at York, in the county of York, State of Pennsylvania, 5 have invented a new and useful Improvement in Railroad-Rail-Joint Chairs, which improvement is fully set forth in the following specification and accompanying drawings, in which—

Figure 1 represents a top or plan view of a 10 railroad-joint chair embodying my invention. Fig. 2 represents a vertical section thereof in line α α , Fig. 1. Fig. 3 represents a vertical section of a modification.

Similar letters of reference indicate corresponding parts in the several figures.

My invention consists of a chair for the joint of railroad-rails, the construction and advantages thereof being hereinafter fully set forth.

Referring to the drawings, A represents a 20 chair for the joints of railroad-rails, the same consisting of the base B and cheeks C C', with the securing and tightening bolts D D', it being noticed that the bolts D are vertical and the bolts D' horizontal, as shown in Figs. 25 1 and 2.

E represents splice-pieces, which are of angular form, the flanges or base portions E whereof embrace the base of the rail, and are extended laterally, so as to rest on the base B 30 of the chair, the bolts D' passing through the vertical portion E' of the splice-piece and the web of the rail, it being noticed that the base is of width somewhat greater than that of the base of the rail and base portions of the splice-pieces E, and the cheeks C C' rise from the base B, so as to embrace the base portions of the 35 splice-pieces. The cheek C is integral with the base B, and the cheek C' separate therefrom and secured thereto by the bolts D, which 40 are passed through the cheek and base and tightened by the nuts D' of said bolts.

It will be seen that the chair may be readily fitted in position and secured by the bolts and nuts, and by its use the strength of the 45 joint is materially increased at its weakest point without making it rigid, while the base of the rail is kept on a common plane, reducing the possibility of lost motion and breakage of the splice. The tightening of the bolts 50 on the cheeks counteracts the tightening of the bolts in the splice proper, and the cheeks being supported by the flanges or base por-

tions of the angle-splice holds the latter down, whereby a vertical support is given to the heads of the rails, instead of an angular support, as the tightening of the angle-splice bolts has a tendency to do. It will also be seen that the angle-splice pieces are subject to the adjusting actions of the bolts D D', that of the bolts D' being lateral, so as to draw said 60 pieces against the web of the rail, and that of the bolts D being vertical, so as to draw the piece downward and against the base of the rail. By this provision there is a two-part adjustment of the splice-pieces, and should the latter 65 become loose, either at their ends or bases, they may be tightened at either place, and thus be held firmly in position, preventing rattling of the parts. The base B is slotted to receive the bolts D, whereby the cheek-pieces C' may 70 be moved inward or outward, according to requirements, while adjusting the same.

F represents a rail or plate, which is extended upward from the cheek C, (see Fig. 2,) and bears against the under side of the head 75 of the rail, thus serving as a guard, chair, support, or stiffener, especially to joints of rails laid on curves.

If desired, one of the splice-pieces may be formed integral with the adjacent cheek, C, as 80 in Fig. 3, and it is evident that the other splice-piece may be formed integral with the cheek C', the latter, however, being separate from the base of the chair.

In Fig. 2 the end of the base B, adjacent to 85 the cheek C', has an upwardly-projecting flange, B', which serves to keep the said cheek more securely in position.

I am aware that it is not new to employ a wedge-piece to keep a bolted fish-plate in position; neither is it new to use fastening devices to secure said wedge-piece in its place, and such I do not broadly claim.

Having thus described my invention, what I claim as new, and desire to secure by Letters 95 Patent, is—

1. A chair for the joint of railroad-rails, having the slotted base A, a splice-piece with parts E' E'', the part E' being in contact with the base, the bolt D', which passes through the part E' and the web of the rail, and the cheek resting on the part E' and secured by the bolt D to the base, substantially as described.

2. A chair for the joint of railroad-rails, hav-

ng a base and cheek-pieces on opposite sides, angular splice-pieces, and vertical and horizontal bolts, said splice-pieces being formed of parts E' E'', the said part E' being in contact with the said base, the cheeks resting on the parts E'' of the splice-pieces and connected with the base of the chair, and the horizontal bolts pass-

ing through the parts E'' of said splice pieces and the web of the rail, substantially as described.

WILSON BROWN.
